UNITED STATES PATENT OFFICE.

EUGENE W. VEST, OF ST. LOUIS, MISSOURI.

VALVE FOR THE GAS-BURNERS OF FURNACES, STOVES, AND RANGES.

1,325,457.

Specification of Letters Patent. Patented Dec. 16, 1919.

Application filed April 8, 1918. Serial No. 227,246.

To all whom it may concern:

Be it known that I, EUGENE W. VEST, a citizen of the United States, residing at St. Louis, in the State of Missouri, have invented certain new and useful Improvements in Valves for the Gas-Burners of Furnaces, Stoves, and Ranges, of which the following is a specification containing a full, clear, and exact description, reference being had to the accompanying drawings, forming a part hereof.

My invention relates to an improved valve for the burners of gas furnaces, gas stoves and gas ranges, and it consists in the novel arrangement and construction of parts hereinafter fully described and particularly claimed.

The object of my invention is to provide an improved gas-valve construction wherein the parts may be quickly disassembled for the purpose of changing the discharge-tip of the injecting gas-nozzle, whenever desired, to change the size of said tip according to the service required.

A further object of my invention is to provide improved means whereby the discharge-orifice of the discharge-tip cannot be completely closed, so that the gas can be turned down but cannot be completely turned off at said tip, and enable the burner to operate when turned down to the limit upon a very small quantity of gas, without the trouble of relighting.

A further object of my invention is to provide a suitable gas-valve, a Bunsen burner, and an air-throat for said burner, all in a single casting, a suitable valve for controlling the entrance of air to said throat, a cam on the stem of said gas-valve, and a mechanical connection between said cam and the said air controlling valve; whereby the turning up or down of the said gas-valve stem will simultaneously regulate the supply of air, to produce the Bunsen flame required for the most efficient and economical consumption of gas.

In the drawings,

Figure 1 is a vertical section of portions of the fire-box of a furnace or stove, or of a range, having my invention applied thereto.

Fig. 2 is a detail front elevation of the connections between the gas-valve stem, the air-valve and the draft-damper at the top of the range or other apparatus to which the invention may be applied.

Fig. 3 is a detail section through the gas-valve casting, taken on the line 3—3 of Fig. 4.

Fig. 4 is a vertical section of the outer portion of the gas-valve, and

Fig. 5 is a detail section of the air-valve shank adjusting-means.

In the present illustration of my invention I have shown but a single small combustion-chamber having a base-section 1 provided with an aperture 2 in which the burner casting is located, to discharge a mixture of gas and air from the central discharge-pipe 3 of said casting, and to simultaneously discharge cold air from the concentric discharge-pipe 4 of said casting upwardly into the said combustion-chamber; as is shown and described more particularly in my two companion applications, of even date herewith, entitled respectively gas-burning system for furnaces, heating-stoves, ranges, &c., Serial No. 227,245, and gas-burners for furnaces, stoves and ranges, Serial No. 227,244.

But it should be understood that my invention is applicable to any shape or size of combustion-chamber or fire-box.

The numeral 5 designates the top of the range, or the top of a fire-chamber connected to the fire-box or combustion-chamber, no matter what form of apparatus my invention is located in, whether it be a range, furnace or stove.

The said burner casting is supported by suitable means, such as a pedestal 6 resting upon the bottom of the ash-box or ash-pit 7, while its upper end carries a common T 8 into which is threaded a tubular shank 9 formed integral with the said casting, and the lower end of which shank is a continuation of the said gas and air discharge-pipe 3, and forms a dirt-receptacle 10, into which dirt and dust from the said discharge-pipe falls, to be removed by a suitable small common scraper inserted into a horizontal clean-out pipe 11 having a detachable cap 12 at its outer end and located for convenient access.

Said combustion-chamber is composed of sections or blocks of fire-clay, or of other highly refractory material, the numeral 13 designating two opposite vertical blocks, which support the top-section 15 of said chamber.

The flame and hot gases from said discharge-pipes 3 and 4 are discharged up-

wardly into and through the said combustion-chamber, which I now designate by the numeral 14, and said flame will impinge upon the underside of the top-section 15 of 5 the burner covering, and then pass up around the opposite edges of said top-section, on their way to some other portion of the range, furnace or stove.

The mixing-tube 16 is threaded into a 10 neck or boss 17 formed integral with the front vertical wall of said burner casting, and the interior of said tube communicates with the said central discharge-pipe 3 by way of a lateral duct or passage 18, and 15 said mixing-tube and the valve thereof may be of any common approved form, although I prefer the improved form herein shown, and described as follows:

The gas-valve casting is formed with a 20 horizontal portion 19 to which the outer end of the said mixing-tube is connected by a common coupling 20, and an air-throat 21 is formed integral with said casting, and extends from the upper side thereof, up- 25 wardly for a short distance, and then outwardly, in substantially the form of the letter L inverted.

Said air-throat 21 has its interior in communication with the interior of said mixing-tube 16 by way of the said horizontal portion 19.

A common reticulated cone or strainer 22 is fixed in said air-throat 21, to strain the air, in the usual manner.

35 An important feature of my invention is the detachable and interchangeable tip 23 at the inner end of the gas-throat 24 of said gas-valve casting, the outer end of said tip being threaded into the threaded inner end 40 of said gas-throat, and provided with a central discharge-aperture 25 which is of somewhat greater diameter than the diameter of the valve 26 which cooperates with it.

Projecting from the front of the gas- 45 valve casting in axial alignment with the mixing-tube and its neck 17, is a tubular or hollow boss 27, which is internally threaded to receive an externally-threaded tubular plug 28, which can be quickly detached from 50 said position whenever access is to be had to the interior of said gas-valve casting.

Said plug 28 carries the said gas-throat 24, which is detachable therewith.

A very quick opening and closing of the 55 gas-valve 26 is secured by means of a screw-thread 29 on the gas-valve stem engaging corresponding threads 30 on the interior of a bore formed in the said plug 28, a metallic washer 31, perforated for the passage there- 60 through of the said stem, closing the end of said bore, to receive the pressure of the stuffing-box gland 32 upon the packing 33, said gland being threaded into the enlarged outer end of said bore.

65 The numeral 34 designates the service

pipe, through which gas is to be supplied to the gas-valve casting, by way of a common shut-off cock 35, common union 36, and the nipple 37, which latter is threaded into the lower part of the said hollow boss 27 of 70 said casting, and communicates with a vertical passage 38 formed in said boss.

The gas passes from the said vertical passage 38 of the said boss 27 into an annular gas-passage 39 formed in the outer tapered 75 periphery 40 of said plug 28, whence the gas flows inwardly to the gas-throat 24 through a series of radial short ducts 41. (See Fig. 3.)

A simultaneous regulation of the entrance of air to the said air throat 21 of the gas-valve casting, the passage of gas through the discharge-aperture 25 to the burner, and the damper 42 which retards the hot expanded gases against their exit 85 from the fire-chamber beneath the said top 5 of the range, furnace or stove, is secured (in the present instance) by means of the following connections, to-wit:

A slide-valve 43, having an opening 44 90 through it, is mounted to slide vertically in dove-tailed guides 45 carried by the front of said air-throat, to more or less close the entrance to the latter, and permit more or less air to pass through the said opening 44 95 into the said throat, as the said valve is moved up or down in its guides by means of a suitable connection with the gas-valve stem 46.

In the present illustration of this part of 100 my invention I have provided a cam, having a suitable throw, and fixed upon the said stem 46 at a point between the said stuffing-box gland 32 and the stem-handle 47, the projecting lip 48 of said cam being embraced 105 by a U-shaped bearing 49 at the lower end of said valve 43, and there being a shank 50 on the upper end of said valve pivotally connected at 51 to one arm of a bell-crank 52 which is pivoted at 53 to the side wall of the 110 range, furnace or stove, and has its other arm provided with a laterally-projecting pin 54 for detachable engagement with any one of a series of notches 55 formed in a horizontal damper rod 56.

The said damper-rod 56 is provided at one end with a common handle 57, and has its opposite end pivoted at 58 to the common crank or lever 59 of the said damper 42; whereby, when the said gas-valve stem is 120 turned by means of its said handle 47 the said cam will turn with it and cause a corresponding movement of the said slide-valve 43, and more or less close the entrance to the air-throat 21; and this movement of said 125 slide-valve will cause a corresponding (and simultaneous) movement of the said damper 42 (as indicated by the dotted lines in Fig. 2), and cause the hot gases to hug the range or furnace top 5, as well as to be more or 130

less retarded in their passage toward some other part of the apparatus, there to be further utilized or discharged, no matter what the position of the gas-valve may be.

ner as is desired, and hence I have provided the slideable lap-joint 62 in the said damper 50 43, which may be adjusted quickly and accurately to produce an accurate adjustment of said parts.

A common lighter-tube or pipe 64 is provided with the usual lighter tip 65, said pipe 55 being connected to the said service pipe 34 and controlled by a common shut-off cock 66.

The operation of my invention will be readily apparent from the above description, and therefore need not be further explained.

I claim the following as my invention:

1. The combination with a range, stove or furnace having a top for its fire-chamber; of a Bunsen burner; the gas-valve stem of said burner; an air-throat for said burner; means for controlling the entrance of air to said throat; a cam on the said gas-valve stem; means at the top of the fire-chamber for directing the hot gases toward said top and to regulate their passage therat; and suitable means for simultaneously moving said gas-valve stem and said air-controlling means for the entrance of air to the said air-throat, as well as said means at the top of the said fire-chamber.

2. The combination in a gas and air regulating device for ranges, furnaces and stoves, of a gas-valve casting; a gas-valve; a mixing-tube; an air-entrance throat communicating with said mixing-tube; the stem of said gas-valve; a cam fixed on said stem; an air-valve arranged to control the passage of air into said throat; means for connecting said cam to said air-valve, whereby the movement of said stem in turning the gas on or off will simultaneously move the said air-valve; and movable stops on said cam to limit its rotation.

In testimony whereof I have signed my name to this specification in presence of two subscribing witnesses.

EUGENE W. VEST.

Witnesses:

FRANCES HOOVER ROSENBAUM,
JOHN C. HIGDON.

5 Suitable movable stops 60 are detachably secured to the said lip 48 of said cam 47 by means of common screws or some similar fastening, to come into contact with the said U-shaped bearing 49 (or some common fixed 10 part of the stove, furnace or range) when said cam is moved to the limit of its rotation in either direction, and thereby limit the extreme movement thereof; and the adjustment of said stops to the desired point on the periphery of said lip will permit a greater or 15 less quantity of gas and air to be used when the gas is turned on or turned down to the desired limit, and thus form a sort of "measure" for the least and greatest quantity of 20 gas and air to be used.

To permit relative adjustments of the said cam, air-valve 43, and the damper 42, I provide a suitable means of adjustment of the length of the said air-valve or its shank 50, 25 and in the present case that means consists in cutting the valve into two parts by a lateral severance at a point just above the location of the common screws 61, which are used to clamp the overlapping parts of the valve 30 together such parts being united by a rabbeted-joint 62, and one of such parts being slotted, as at 63, for the purpose of permitting one part to slide upon the other part in making the valve or its shank longer or shorter, 35 as the best practice shall dictate, in adjusting the relative positions of the valve and the said damper; and such a joint in the valve-connections will also be useful in taking up wear or lost motion of the connected 40 parts between said valve and said damper. (See Fig. 2).

The same object may, of course, be accomplished in a measure by adjusting the said damper-rod 56 in its relation to the pin 54 45 of the said bell-crank 52, by causing said pin to rest in the desired notch 55 of said damper-rod; but such adjustment cannot be made as accurately or satisfactorily in that man-
